UNITED STATES PATENT OFFICE.

WALTHER RASTER, OF CHICAGO, ILLINOIS.

SIGN.

1,072,870.

Specification of Letters Patent.

Patented Sept. 9, 1913.

Application filed April 28, 1913. Serial No. 764,066.

To all whom it may concern:

Be it known that I, WALTHER RASTER, a citizen of the United States, residing at Chicago, in the county of Cook and State 5 of Illinois, have invented certain new and useful Improvements in Signs; and I do hereby declare the following to be a full, clear, and exact description of the invention, such as will enable others skilled in 10 the art to which it appertains to make and use the same.

My invention relates to improvements in changeable signs for advertising and other purposes, and particularly to signs adapted 15 for use in show windows and adjacent to the glass panes of doors in stores and the like.

The prime objects of my invention are to provide a simple, compact and cheaply constructed sign which may be read from either side; to provide a simple mechanism operated automatically upon the opening or closing of the door to which the sign is attached, for shifting portions of the sign 25 so as to change the legend upon both sides thereof; and to provide a holder in which the sign portions may easily be exchanged or replaced, and in which the operating mechanism will serve to hold the sign portions 30 in position.

While the device of my invention may be used in many different positions, it is particularly adapted for attachment to a store door immediately above the door-knob and 35 is shown in this embodiment in the accompanying drawings in which:

Figure —1— is an elevation of a door having the changeable sign of my invention attached thereto. Fig. —2— is a side elevation of the door showing a portion of the operating mechanism of the device of 40 my invention. Fig. —3— is an enlarged elevation of the sign portion of my device. Fig. —4— is a section through Fig. 3 along the line 4—4. Fig. —5— is a longitudinal section through Fig. 3 along the line 5—5. Fig. —6— is a top or bottom view of one of the relatively movable members comprising the body or face of the sign. Fig. —7— is an elevation of the same. Fig. —8— is an enlarged top or bottom view 45 of the intermeshed pair of members comprising the face of my sign. Fig. —9— is a perspective view of one of the intermeshed members of my sign.

In the embodiment shown in the draw-

ings, the device of my invention comprises a frame housing a fixed and a movable sign member; a lever adapted to reciprocate the movable member; a pair of unequal springs tending to draw the lever to its respective 60 opposite position; and a cam plate attached to the frame of the door and adapted to compress the stronger of said springs, thereby permitting the weaker spring to 65 control the position of the lever and hence of the movable sign member.

The sign proper consists of a pair of companion members 1 and 2, each being a sheet metal plate having a series of tongues 70 punched therefrom, the said tongues being equal in size and extending in the same direction. After punching each of the said tongues, or simultaneously with the said punching, I form a transverse bend in the 75 strip portions of the plate extending laterally at opposite sides of the tongue and adjacent to the base of the tongue, thereby providing an offset which will cause the successive tongues to lie in separated but parallel 80 planes. It will be evident from Figs. 6 and 9 that the transverse portion of each bend thus formed will provide a slit or aperture equal in length to the width of the tongue and through which slit the tongue of a similar 85 companion member may be inserted from the opposite direction. At the same time, the forming of the offset in the lateral strip portions of the plate shortens or longitudinally contracts the said strip portions so that the tip of each tongue will project longitudinally beyond a portion of the 90 material from which the said tip of the tongue was severed. Each of the said companion members has letters or sign portions 95 positioned upon each side thereof, and when the tongues of each of the companion members are slid respectively through the slits adjacent to the tongues in the other member, it will be evident from the drawings that the 100 portions of the two members between the strip portions will overlap or underlap so as to conceal some of the said sign portions. By suitably proportioning the travel or length of relative motion of the sign members, each 105 tongue when in one extreme position will conceal one side of the adjacent sign portion of the tongue and of the material adjacent to the base of the tongue of the companion member; and when moved to the 110 other extreme position, each of the said tongues and parts adjacent thereto will be

concealed by a portion of the companion member and will disclose the sign legend upon that side of the latter. Since the two members are similar and symmetrical, this alternate concealing and revealing of the pair of legends upon each side of both of the companion members will be simultaneous, so that the sign may be read simultaneously from both sides thereof when positioned as in Fig. 1. Owing to the shortening of the body of the strip with respect to the tongue portions thereof, the tip of each tongue will lap longitudinally beyond the edge of the material from which this tip was severed, the excess in the length of each tongue serving as a guard to prevent the intermeshed tongue of the other sign member from slipping out of its overlapping or underlapping position.

In equipping my sign for use upon store doors, I assemble the pair of sign members 1 and 2 with their respective tongues and slits interengaged and slide the pair of sign plates into a channel steel frame 3 attached to the frame of the door by screws 4. I then hookingly attach a link 6 to one of the companion members 2, the other end of this link being pivoted to a bell-crank 7 which has a spring 8 tending to draw it in one direction, this spring being normally overbalanced by a wire spring 10 connected to the rocking lever 7 by a wire 9. The lever 7 and spring 8 are preferably mounted in a frame 5 which may be separated from the frame 3 and which abuts against the sign plate 1 when fastened in place by screws 11, thereby holding the said plate against sliding. By removing the screws 11, the frame 5 and the operating mechanism carried thereby can readily be detached, thereby permitting the sign plates to be reversed or others to be substituted for them. The stronger spring 10 is preferably positioned close to the upper edge of the door and in the path of a cam-plate 12 adapted to engage this spring and to bend it downwardly when the door is closed, thereby releasing the upward tension on the wire 9 and permitting the spring 8 to rock the lever 7 and move the movable sign plate 2 in Fig. 3 to the left-hand extreme of its travel. As soon as the door is opened sufficiently to move the spring 10 out of engagement with the cam-plate 12, the said spring will resume its upward tension upon the wire 9, thereby overbalancing the spring 8 and returning the plate 2 to the right-hand extreme of its travel.

To insure an easy sliding of the members relative to each other without requiring great exactness in the positioning of the parts thereof, I preferably make both members of the same thickness of material and give each of the transverse or offset bends a height somewhat greater than double the thickness of either member, thereby provid-

ing slits considerably wider than the thickness of the tongues which slide through the said slits. It will be noticed that the bends in each member serve to divide the same into a series of portions lying in parallel planes; each of which portions comprises in a single plane a tongue narrower than the width of the member, a full width portion to which the tongue is attached at its base, and a pair of edge portions lateral of (but not in the same plane with) the next successive tongue.

To prevent the overlapping and underlapping sign portions from rubbing against one another (thereby scraping and possibly disfiguring the face portions of the signs) I preferably provide a ridge or rib 16 upon each sign member, which rib will act as a spacer to prevent a contacting of the tongues and the sign portions longitudinally thereof. Since the sign members have different legends exposed upon the portions disclosed respectively in the two positions between which these members are relatively movable, any person opening or closing the door will automatically change the legend of the sign directly in front of him, thereby encountering two different legends when entering the store and two others when leaving the same.

While I have shown the sign of my invention as adapted to a particular location and as operated through the opening and closing of a door, it is evident that it could be adapted to operate in many other conditions; also that the alternative overlapping and underlapping sign members could be operated by other means than the ones disclosed in the drawings. I therefore do not wish to be limited to the particular embodiment here shown and described, as it will be evident that numerous modifications might be made in the same without departing from the spirit of my invention as embodied in the accompanying claims.

I claim as new and desire to cover by Letters Patent:

1. A sign comprising a pair of slidably interfitting members each having a plurality of tongues extending in the same general direction, there being adjacent to the base of each tongue an offset bend in the portions of the member at each side of the said tongue, whereby each member is bent into a series of portions lying in parallel planes; each of said portions comprising in a single plane a tongue narrower than the width of the member, a full width portion to which the tongue is attached at its base, and a pair of edge portions lateral of the next successive tongue.

2. A sign comprising a pair of slidably interfitting members made of materials of substantially equal thickness, each having punched therefrom a plurality of tongues

extending in parallel planes in the same general direction, there being adjacent to the base of each tongue an offset bend in the portions of the member at each side of the 5 said tongue, the height of each of said bends being greater than double the thickness of the material from which each of the members is formed, whereby the said bands afford slits of greater width than the thickness of the said tongues.

3. A sign comprising a pair of members each having punched therefrom a plurality of tongues extending in the same general direction, there being an offset bend in each 10 member laterally of each tongue whereby the consecutive tongues are positioned in parallel planes, the space between the tip of each tongue and the material from which this tip was punched forming a slit, the 15 tongues of each member projecting respectively through the slits of the other member, the said members relatively reciprocable in the direction in which their tongues extend, whereby each tongue is adapted to 20 expose and conceal one side of the adjacent tongues of the other member upon relative reciprocation of the members.

4. A sign comprising a pair of members each having a plurality of tongues extending in the same general direction and having adjacent to the base of each tongue an offset bend in the portions of the member at each side of the said tongue, whereby each member is bent into a series of portions lying in parallel planes, and whereby the said bends afford slits in each member through which the tongues of the opposite member may be slidably inserted; there being ridges upon the lateral portions of one of the said 35 members, the said ridges adapted to bear against lateral portions of the companion member.

5. A sign comprising a pair of members each having a plurality of tongues, the said 40 members movable from one to another of two relative positions; the tongues of one member lapped over and concealing portions of the companion member, or lapped under and concealed by other portions of 45 the companion member, according as the

members are in one or the other of their said relative positions; the portions of each member on opposite sides of each tongue being shortened longitudinally, whereby the tip of each tongue projects longitudinally beyond a portion of the material from 55 which the said tip was severed, the excess in length of the tongues serving as a guard to prevent disengaging of the tongues from their said lapped positions.

6. A sign comprising a pair of sign members operating mechanism connected to one of the latter, a frame slidably housing the said members and adapted to receive the said mechanism, and means for securing 60 the said mechanism to the said frame; the said mechanism abutting against the other of the said sign members to hold the same non-slidably in the said frame when the mechanism is secured thereto.

7. In a sign, a pair of relatively movable sign members, and mechanism for relatively moving the same comprising a lever, a pair of springs of unequal strength tending to force the said lever in opposite directions, connections for imparting the motion of the lever to one of the sign members to move the latter, and a cam member for 75 relieving the pressure of the stronger of the said springs.

8. In a sign for use upon a door, a pair of sign members mounted upon the door, mechanism for moving one of the said sign members with respect to the other; a pair of springs of unequal strength tending to 80 operate the said mechanism in opposite directions the stronger of the said springs mounted upon the door adjacent to the frame thereof; a cam-plate mounted upon the door frame and adapted to engage and 85 overcome the pressure of the said stronger spring upon the closing of the door.

In testimony whereof I have signed my name in presence of two subscribing witnesses.

WALTHER RASTER.
